(57) **CLAIM**

The ornamental design for a remote control, as shown and described.

DESCRIPTION

FIG. 1 is a front elevation view for a remote control of the present invention;

FIG. 2 is a rear elevation view thereof;

FIG. 3 is a side elevation view, the right and left side views being mirror images thereof;

FIG. 4 is a top plan view thereof;

FIG. 5 is a bottom plan view thereof; and,

FIG. 6 is a perspective view thereof.

1 Claim, 5 Drawing Sheets
